(57) **CLAIM**

The ornamental design for a watering cone as shown and described.

DESCRIPTION

FIG. 1 is a first perspective view of a watering cone according to our new design;

FIG. 2 is a second perspective view thereof;

FIG. 3 is a third perspective view thereof;

FIG. 4 is a fourth perspective view thereof;

FIG. 5 is a front elevation thereof;

FIG. 6 is a rear elevation thereof;

FIG. 7 is a left-side view thereof;

FIG. 8 is a right-side view thereof;

FIG. 9 is a top view thereof;

FIG. 10 is a bottom view thereof;

FIG. 11 is a further perspective view of the watering cone with additional environment disclaimed;

FIG. 12 is another perspective view thereof;

FIG. 13 is a further perspective view of the watering cone with additional environment disclaimed;

FIG. 14 is a front elevation view thereof;

FIG. 15 is a rear elevation view thereof; and,

FIG. 16 is a bottom plan view thereof.

The broken lines in the drawings depict environmental subject matter that is hereby disclaimed and forms no part of the claimed design. In particular, the broken lines in FIGS. 11-16 depict environmental structure in the form of a water hose and spike showing the watering cone securing the water hose around the spike. In FIGS. 13 and 14, the disclaimed water hose has been removed for clarity reasons. Conventional shading is illustrated for purposes of highlighting the line drawing, but forms no part of the claimed design.

1 Claim, 16 Drawing Sheets
